RESERVOIR INKWELL

Joseph Clarence Gilbert, Dallas, Tex., assignor
of one-third to R. F. Gildehaus, Jr., Dallas,
Tex.

Application August 27, 1928. Serial No. 302,389

10 Claims. (Cl. 120—59)

This invention relates to improvements in receptacles for ink or other liquids, and particularly to such receptacles as employ the "constant head principle" for maintaining the liquid level in a well associated with a reservoir.

The invention is especially adapted for use as an ink well, but this reservoir container may be used to hold many other substances, especially those subject to high evaporation, such as paints, lacquers, thinners and glues.

One of the primary objects of the present invention is to furnish an ink well including a pen well and reservoir, the reservoir being of such size as to contain a relatively large supply of ink, and the pen well being relatively small, so as to hold only a small amount of ink; the parts being combined with a constant head tube, whereby the ink in the pen well is maintained at a substantially constant level.

Another object of the invention is to provide an ink well of this character, in which the reservoir has only a single opening and that communicating with the pen well, so that the reservoir when resting in its normal position, will always remain sealed or air-tight, due to the opening being sealed with the ink.

A further object is to provide an ink well of this type, in which one of the side walls of the reservoir is shaped to form an auxiliary base, whereby when the well is turned so as to rest on this auxiliary base, the reservoir may be filled by pouring the ink in through the pen well.

Another object of the invention is to furnish the reservoir of this well with a constant head tube having an air inlet end terminating through any side of the reservoir other than the top of the reservoir.

A further and important object is to furnish a combined reservoir and pen well with a flood chamber or chambers communicating with the pen well, whereby when, due to changes in atmospheric pressure, or changes in temperature, excessive ink is forced from the reservoir into the pen well, the excess ink may overflow into the flood chamber or chambers, and thereby prevent flooding of the pen or dip well.

With the foregoing objects outlined and with other objects in view which will appear as the description proceeds, my invention consists in the novel features hereinafter described in detail, illustrated in the accompanying drawings, and more particularly pointed out in the appended claims.

Referring to the drawings,
Fig. 1 is a vertical sectional view of what I now

consider the preferred form of the invention, taken on line 1—1 of Fig. 2.

Fig. 2 is a horizontal sectional view of the same, taken on line 2—2 of Fig. 1.

Fig. 3 is a transverse vertical sectional view on line 3—3 of Fig. 1.

Fig. 4 is a transverse vertical sectional view of a detail, taken on line 4—4 of Fig. 1.

Fig. 5 is a vertical sectional view of a modification, in which the reservoir is much larger than the reservoir of the main embodiment of the invention, and in which some of the parts are shaped differently from the main embodiment.

Fig. 6 is a longitudinal horizontal sectional view, taken on line 6—6 of Fig. 5.

Fig. 7 is a vertical transverse sectional view of a detail taken on line 7—7 of Fig. 5.

Fig. 8 is a sectional view on the line 8—8 of Fig. 1.

In the embodiment of the invention illustrated in Figs. 1 to 4 and 8 inclusive, the main parts may be made of a single piece of glass or the like, forming a plural compartment receptacle. This receptacle includes the supply reservoir 10 which has a top 11, an inclined front wall 12, step shaped side walls 13, a bottom 14, and a plain rear wall 15 which is adapted to act as an auxiliary base when the receptacle is turned upwardly, so as to rest on the wall 15. This is for filling purposes, and will be referred to hereinafter.

A vertical partition 16 extends transversely across the forward portion of the receptacle and connects the top and bottom and the side walls of the reservoir 10, and this partition separates the reservoir from a dip well or pen well 17.

It will be observed that the reservoir 10 is entirely closed with the exception of a single opening 18 which is arranged at the lower end of the partition, and places the reservoir and dip well in communication.

Vertical ribs or partitions 19 extend forwardly from the partition 16 at opposite sides of the pen well, and assist in forming flood chambers 20, which extend into the stepped portions of the side walls 13, as best shown in Fig. 3.

Openings or ports 21, place the flood chambers in communication with the pen well.

A feeding member 22, formed of any suitable material, is arranged mainly within the dip well, and extends through the opening 18, into the reservoir 10, and this member is provided with a central trough 23, and with inverted side troughs 24, the latter communicating with the reservoir 10 by means of apertures 25. The member 22 allows ink to flow through the trough 23, and air to flow

through the troughs 24 and apertures 25 during filling of the reservoir.

The structure also includes a pen tube or holder 26 that extends through an aperture in the top 5 of the pen well, and is detachably connected to said top by a bayonet joint 27. This tube has longitudinal grooves 28 in its bore, (see Fig. 8) so as to allow air to flow past a pen holder, while the latter is occupying the tube.

10 The grooves 28 admit air pressure to the space in the pen well when the pen staff, which fits the bore, is inserted in said tube. In this position, the admittance of dust is practically eliminated by the pen staff, and evaporation is reduced to a 15 minimum because, air circulation cannot take place to any appreciable extent. Evaporation of ink in the pen well occurs only to the amount required to saturate the small quantity of air within the pen well, and if this air is not displaced 20 through circulation, further evaporation cannot take place.

A constant head tube 29 for admitting air to the reservoir 10 has its outlet end connected to the front wall of the reservoir at a point 30 which 25 is below the top 11, and the lower end of this tube extends to a point where the liquid level in the pen well is to be maintained. This tube maintains, at constant temperature and atmospheric pressure or falling temperature and pressure, the 30 liquid level in pen well 17, at a height H, said height being either above or below the floors 31 of the flood chambers, as desired.

The air inlet end of the tube 29 may be at any suitable location, so long as it is above the tube 35 end terminating within the reservoir, but in my construction, it is below the normal top and in a particular side, so that ink cannot run out of it when filling the well. This particular side is the one opposite the auxiliary base, because it becomes the "top" when the well is turned on its auxiliary base for the purpose of filling. The air inlet of the pressure tube should terminate opposite the auxiliary base at a point above the 40 level of ink existing in the reservoir, when the ink well is resting on said auxiliary base, and the reservoir is full.

It is preferable to have the height H above the flood plane level, so that the planes or floor surfaces of the flood chambers will always be covered 50 with liquid to prevent ink drying on the planes when the level recedes to the height H after flooding.

When the ink well is exposed to increasing temperature, the air in the reservoir 10 will expand, thus forcing ink through opening 18, out into the pen well 17. Expansion will cease when the partial pressure of the air, plus the height of liquid in the reservoir, above the lower end of the tube 29, equals the pressure of the atmosphere, which 60 acts at the lower end of the tube.

In order to minimize this rise of liquid in the pen well 17, the flood chambers 20 are provided, and they have ample surface over which the liquid forced out of the reservoir by the expanding air, 65 may spread. It is manifest that with sufficient surface, the rise of the liquid can be held to a very small amount, so small in fact, as to make no material or objectionable difference in the quantity of ink taken up by the pen inserted in the pen well from time to time.

With falling temperature, any ink in the pen well 17, above the height H, will be drawn back into the reservoir, through passage 18, until equalization of the pressure at the lower end of the 70 tube 29 has been restored. If the temperature

should continue to fall after the ink in the pen well is lowered to the height H, air will pass into the reservoir through the tube 29, until the pressure balance is reached.

To fill the reservoir, the pen sleeve 26 is removed from the top of the pen well, and the device is then set up on its side wall 15, which at this time, functions as a temporary base. The ink is then poured from a suitable container into the well 17, from which it will flow into the reservoir 80 10. The wings 19, at this time, form a chute which directs the flow of the ink to the passage 18, and prevents the ink from flowing into the flood chambers.

The member 22 fitted into the passageway 18, 90 extends into the reservoir 10, far enough to expose the holes 25, and as before stated, it is shaped to divide the opening 18 into three passageways. The central one of these passageways, allows the ink to flow from the pen well into the reservoir 10, 95 while the side passageways permit the air displaced within the reservoir to pass out to the atmosphere without interference with the flow of ink into the reservoir. When the reservoir has been filled up to the member 22 and the ink closes 100 the inner ends of the side passageways, the remaining air may escape through the holes 25, as the filling is completed.

When filled, the ink well is simply turned on to its normal base 14, and the ink will flow through 105 the opening 18, into the pen well to the height H. The pen sleeve 26 is then restored to its original position, and the ink well is ready for use.

It may be stated that it is not necessary to completely fill the reservoir, as it may be partially 110 filled to any convenient amount. It is also unnecessary to empty the ink well before filling, and ink may be added from time to time, as desired, whether the ink well is partly full or empty. As only a small quantity of the ink is open to the atmosphere, it is obvious that the present device will conserve the ink to a great extent.

The grooves 28 in the pen sleeve, permit equalization of air pressure in the pen well with the atmosphere, while a pen holder occupies the sleeve. 115 Instead of a pen sleeve of the character disclosed, a cap (Fig. 5) may be provided for the opening in the top of the pen well. Such cap should be fitted to prevent admission of dust and appreciable evaporation, but it should not be air-tight.

If suitable closures are provided for the tubes 26 and 29, it is obvious that liquid may be safely shipped within the container.

It will be readily seen that this invention may be embodied in the form of containers of many 120 different shapes and proportions, other than those shown in Figs. 1 to 4 inclusive. For instance, it may be embodied in a structure of the character shown in Figs. 5 to 7 inclusive. In this form of the invention, the side wall of the reservoir is circular in shape, and includes an upper portion 50, and a lower portion 51. These parts may be detachably connected together as shown at 52, in order that the parts 50 and 51 may be more readily cleaned, said detachable connection being 125 of such nature that when parts 50 and 51 are joined together and the ink well is resting in its normal position, the reservoir will be sealed or air tight. Instead of being detachably connected, these parts may be permanently joined at 52 in 130 manufacture, so that the reservoir, when the ink well is resting in its normal position, will always be sealed or air tight, once it is so made.

In this form of the invention, a single flood chamber 53 of annular shape is used, and this 135

chamber communicates with the pen well 54 at the points 55.

This form of the invention operates in the same manner as the structure shown in Figs. 1 to 5 4 inclusive, and filling is accomplished in a similar manner. The pen sleeve is removed and the ink well is turned over to rest on flat portion 56, Fig. 6, formed in the base opposite the pen well, which flat portion prevents the ink well 10 from tipping or rolling while ink is poured into the pen well until the reservoir is filled.

While I have disclosed preferred embodiments of the invention, I am aware that various changes may be made in the details disclosed, 15 without departing from the spirit of the invention, as expressed in the claims.

What I claim and desire to secure by Letters Patent is:

1. A container comprising mainly a reservoir 20 and a dip well, having a flood chamber communicating with said reservoir through the dip well, said flood chamber being formed by an enlargement of said dip well arranged adjacent to a portion of said reservoir, said flood chamber of such 25 size relative to capacity of said reservoir as to maintain the rise of liquid in the dip well within a desirable limit, when the said container is subjected to normal range of temperature change.

2. In an ink well, a receptacle divided internally by partitions to form a reservoir, a pen well and a flood chamber, having a capacity greater than the pen well communicating directly with the pen well, and the pen well communicating with the reservoir, said pen well having an 30 opening to atmosphere, and an air tube extending downwardly through one wall of the reservoir and terminating at a level in substantially the same plane as the floor of the flood chamber.

3. In an ink well, a closed reservoir, a smaller 40 pen well communicating with the reservoir through a suitable opening, the well having a port to permit a pen to be dipped into the latter, an air tube extending through a wall of the reservoir and terminating at a level below the top of the pen well, and means arranged in the opening between the reservoir and pen well for guiding ink from the well into the reservoir during the filling of the latter, while maintaining said ink out of contact with air discharging through 45 said opening.

4. An ink well, including a relatively large reservoir and a smaller ink chamber communicating with each other through an opening, and a corrugated member extending through said opening and having air ports extending through the portion of the member which extends into the reservoir.

5. In an ink well, a reservoir, a pen well, the well having a port placing the reservoir and well 50 in communication, and a corrugated member extending through said port and having ridged portions provided with openings to permit air to escape from the reservoir while ink is flowing

from the well to the reservoir on the corrugated member.

6. In an ink well, a dip well, a reservoir, the well having a port placing the well and reservoir in communication, said well having an opening to permit a pen to be dipped in the latter, an air tube extending through one wall of the reservoir and terminating within the latter in close proximity to said port and at a predetermined height from its bottom, wings arranged at the 80 sides of the pen well, and flood chambers communicating with said well and arranged at opposite sides of the reservoir.

7. In an ink well, a receptacle including a reservoir having stepped shaped side walls, a partition arranged in the receptacle and joining the forward ends of said side walls, said partition dividing the receptacle into a plurality of compartments, one of said compartments forming a pen well and the other forming said reservoir, wings in the receptacle forming the side walls of the pen well, flood chambers arranged within the receptacle and extending along the stepped portions of said side walls, and ports placing the pen well in communication with the 95 reservoir and flood chambers.

8. In a structure of the character described, a receptacle divided internally by partitions to form a reservoir, a pen well and flood chambers, the flood chambers being arranged above the bottom 105 of the pen well and communicating with the latter in such manner as to receive ink from the well when the level of the latter rises unduly in the reservoir below the flood chambers, said pen well 110 having an opening to atmosphere, and an air tube extending downwardly through one wall of the reservoir and terminating at a level in substantially the same plane as the floors of the 115 flood chambers.

9. In an ink well, a receptacle divided internally by partitions to form a reservoir, a pen well and flood chambers, the flood chambers being positioned above the lower portion of the well and communicating with the well, means placing the 120 reservoir in communication with the pen well, a pen supporting tube extending upwardly from the well, and an air tube extending downwardly through one wall of the reservoir and terminating at a level in substantially the same plane as the 125 floors of the flood chambers.

10. In an ink well, a reservoir which is closed except the opening through which the ink is normally taken, said ink well having a normal base and an auxiliary base which is used when the reservoir of the ink well is being filled, and a constant head tube with the air inlet end terminating opposite said auxiliary base, at a point above the level of ink in the reservoir existing when said container is resting on said auxiliary 130 base, and the reservoir is full.

JOSEPH CLARENCE GILBERT.
